CLAIM

The ornamental design for a web enabled audiovisual medication dispenser, as shown and described.

DESCRIPTION

FIG. 1 is an isometric view of a web enabled audiovisual medication dispenser showing our new design;

FIG. 2 is a front elevational view;

FIG. 3 is a left side elevational view, with the right side elevational view being a mirror image thereof;

FIG. 4 is a back elevational view;

FIG. 5 is a bottom plan view; and,

FIG. 6 is a top plan view.

In the drawings, the evenly-spaced broken lines depict portions of the article that form no part of the claimed design; the dash-dot-dash lines represent the boundary of the claimed design and forms no part thereof.

1 Claim, 4 Drawing Sheets
